(57) CLAIM

The ornamental design for a storage rack cover, as shown and described.

DESCRIPTION

FIG. 1 is a front, right side perspective view for a storage rack cover, showing my new design;

FIG. 2 is a front elevational view of FIG. 1 thereof;

FIG. 3 is a rear elevational view of FIG. 1 thereof;

FIG. 4 is a left side elevational view of FIG. 1 thereof, the right side elevational view being a mirror image;

FIG. 5 is a top plan view of FIG. 1 thereof; and,

FIG. 6 is a front right side perspective view of FIG. 1 thereof, the storage rack cover in an open state.

The broken lines indicate unclaimed portions of the storage rack cover and form no part of the claimed design.

1 Claim, 6 Drawing Sheets
